UNITED STATES PATENT OFFICE.

ROBERT P. GROSS, OF LOS ANGELES, CALIFORNIA.

DESIGN FOR A CONTAINER FOR TOILET ARTICLES.

Application filed September 5, 1922. Serial No. 3,634. Term of patent 14 years.

To all whom it may concern:

Be it known that I, ROBERT P. GROSS, a citizen of the United States, residing at Los Angeles, in the county of Los Angeles and State of California, have invented a new, original, and ornamental Design for a Container for Toilet Articles, of which the following is a specification.

Reference is had to the accompanying drawing, forming a part of said specification, in which—

Figure 1 is a front elevation showing my new design; Figure 2 is a plan view of the same; and Figure 3 is a fragmentary section taken on the line 3—3 of Fig. 2.

I claim:

The ornamental design for a container for toilet articles, as shown.

ROBERT P. GROSS.
